(57) **CLAIM**

I claim the ornamental design for a combined wrist watch, wrist computer and diving computer, as shown and described.

DESCRIPTION

FIG. 1 illustrates a perspective view of a combined wrist watch, wrist computer and diving computer of the present invention;

FIG. 2 illustrates a front view of the combined wrist watch, wrist computer and diving computer of the present invention;

FIG. 3 illustrates a rear view of the combined wrist watch, wrist computer and diving computer of the present invention;

FIG. 4 illustrates a top view of the combined wrist watch, wrist computer and diving computer of the present invention;

FIG. 5 illustrates a bottom view of the combined wrist watch, wrist computer and diving computer of the present invention;

FIG. 6 illustrates a right side view of the combined wrist watch, wrist computer and diving computer of the present invention; and,

FIG. 7 illustrates a left side view of the combined wrist watch, wrist computer and diving computer of the present invention.

The broken lines of FIGS. 1-7 are for illustrative purposes only and form no part of the claimed design.
